HYDRAULIC TURBINE

Original Filed Nov. 13, 1923

UNITED STATES PATENT OFFICE

LEWIS FERRY MOODY, OF PHILADELPHIA, PENNSYLVANIA

HYDRAULIC TURBINE

*Original application filed November 13, 1928, Serial No. 674,461, and in Canada October 16, 1924. Divided and this application filed April 16, 1926, Serial No. 102,404. Renewed November 12, 1928.

This invention relates to hydraulic turbines and particularly to draft tubes for the same. The object of the invention is to provide a draft tube which while simple and inexpensive in construction will be efficient in operation and especially adapted to decelerate the flow within a limited space. Another object of the invention is to provide a draft tube suitable for turbines of high specific speed. 10 Further objects of the invention, particularly in providing a draft tube structure having a series of concentric annular passages in position below the runner, will appear from the following description and the accompanying drawings.

By dividing the draft tube passage into a number of passages each receiving a part of the total flow, it becomes possible to decelerate the velocity of discharge from the runner and 20 to convert its kinetic energy into useful head within a smaller space than would be possible if a single passage were used, and to accomplish this without sacrifice of draft tube efficiency. The reason why this can be accomplished may be understood by considering a simple passage of rectangular cross-section having a pair of opposite sides diverging at a small angle. Such a passage will decelerate the flow, and it is known that the efficiency of 25 the energy conversion is dependent on the angle of divergence of the sides. If the angle is increased beyond the best value in the effort to produce the deceleration in a shorter length of passage, internal eddies are caused in the flow and the efficiency of conversion is impaired. If, however, a partition is interposed midway between the diverging walls, the angle of divergence between the partition and each wall is cut in half; and each of the 30 new passages thus formed may have the most favorable angle of divergence, and the outer walls of the original passage will then have twice the angle of divergence which would be permissible without the partition. This 35 principle of securing rapid deceleration within a restricted length of passage by subdivision, when applied to conical or flaring annular passages, results in the forms of draft tubes described herein.

In the specific embodiment of the invention shown in the drawings,

Fig. 1 is a vertical section of a turbine installation embodying the invention,

Fig. 2 is a vertical sectional view of a turbine unit,

Fig. 3 is a fragmentary sectional view of a modified form of the invention.

In the turbine shown in the drawings a floor 48 extends down stream from the headwater H and above this floor is an entrance space or flume E forming an admission passage leading the water to the turbine and extending above and around the fixed guide vanes 36 providing the entrance to the turbine. The flow passing in through these guide vanes 36 and down through the runner R is discharged into the draft tube emptying downwardly and outwardly into a discharge chamber D leading to tailwater T. The outer wall of the draft tube is formed as a liner casting 53 embedded in the concrete of the floor 48 and at its lower end this liner casting carries the projecting extension 53 of generally conical form and constructed of plate metal bent into the form of a skirt suspended from said casting 52. The central conical core 54 is similarly formed of plate metal bent into the form shown and provided with a cap member 55 under the hub of the runner R. The intermediate partitions 56, 57 are similarly formed of a series of plate sections bent into generally conical form and nested one over the other by lap joints as shown. All of these plate metal members are connected together by the straps or stays 60 at their discharge edges. These stays may be inclined as shown to suit the direction of flow. The flow from the runner is received in a substantially axial direction and turned outward toward a radial direction and decelerated in the upper portion of the draft tube, and in the lower portion of the draft tube the flow is spread and decelerated all around between concentric conical walls.

This plate metal construction of the draft tube is inexpensive and easily formed and gives a higher rate of deceleration of the outflow within a small space (see Fig. 1) being suspended from the floor 48 of the flume.

This draft tube permits the outlet chamber 58 to be of any desired form and, where desired, the central conical core 54 may be continued down to be supported from the floor of this chamber as indicated at 59, or in the modification shown in Fig. 3 the core 54 may terminate short of the floor thereby being of substantially the same length as the partitions.

10 The intermediate partitions 56, 57 in dividing the draft tube into a plurality of passages permit a higher rate of deceleration without departure of the flow from the draft tube surface, because each passage can have 15 the permissible rate of increase in area independently of the other passage and the total permissible rate of increase in area is thus approximately tripled, according to the principle previously explained. This makes 20 it possible to accomplish the desired deceleration of the flow within a much shorter length of draft tube, reducing the size and cost of the structure. The walls 52, 53, 54, 56, 57 being formed as surfaces of revolution offer 25 no obstruction to the whirling components of the outflow, and by smoothly spreading and turning this outflow the annular draft tube passages formed by the annular walls thereof are adapted to recover both the meridian 30 and whirling components of velocity.

While the draft tube of this invention is applicable to turbines of all types, it is particularly advantageous for turbines of high specific speeds, such as the propeller type turbines shown in the figures. In turbines of low and moderate specific speeds there is a strong tendency at partial gate openings for the discharge to take place through only a part of the runner, namely, that near the 40 outer periphery. The draft tube thus receives a ring of downward flowing water around its outer wall, the inner portion being subject to water not progressing downward but subject to local turbulence and, near 45 the axis, to upward flow into the runner. In turbines of high specific speed, this tendency is still more pronounced, and takes effect through a large range of gate openings and even at normal gate in such turbines the flow 50 through the runner may be very unequally distributed. Attempts to improve the turbine performance by subdividing the runner by the addition of intermediate shroud rings 55 or diaphragms in order to separate the flow into distinct annular zones have not shown any material improvement; and in high specific speed turbines such diaphragms in the runner are very objectionable from the 60 great increase in surface friction which they impose due to the high relative velocity between the runner and the water. I therefore 65 avoid the use of any shroud rings or diaphragms in turbines of high specific speed; and in order to improve the conditions in the

draft tube I add one or more partitions or diaphragms in the draft tube.

At times when there is a tendency toward a considerable reduction or a reversal of flow near the runner hub there is at the same time a large whirl or rotational component about the axis in the water below the runner. By providing a separate annular passage for the water in the inner portion of the draft tube, and by leading this passage outward away from the axis so that the water passing through it materially increases its radial distance from the axis in passing from the entrance to the discharge of the passage, I obtain a tube in which the centrifugal force of the contained water sets up an outward pressure and maintains a low pressure at the runner discharge. I also provide a solid core in the central portion of the tube to avoid the extreme conditions of whirl and inefficient flow, and even the creation of a cavity, which are likely to occur near the axis.

When small space and reduced first cost are of great importance, as in low or medium head plants, the form of tube shown in Figs. 1 and 2 may be used, in which the innermost passage is not carried to as great a radial distance from the axis as the outermost, but a large total area of discharge for the entire draft tube is provided within a small space. In this form of tube the discharge takes place through almost the whole of the portion of the spherical surface bounded by the discharge edge of the outer wall of the draft tube, the only part of this area which is not utilized for the discharge flow being the relatively small area of the base of the central core, and the space taken up by the thickness of the metal in the partitions.

In one aspect of the invention the draft tube acts as a diffusing nozzle for converting the velocity of fluid into pressure by the provision of passages the opposing walls of which enclose angles of substantially 10°. This is the case between the lower sections 53, 56 and 57, these sections comprising a substantial portion of the whole draft tube. This results in a multiple passage arrangement having a total outlet aperture or area considerably larger than that which could be obtained with a single passage nozzle having the same length and the same size of inlet orifice.

The structure of this invention provides a turbine of simple and inexpensive form and of small overall dimensions. The suspension of the draft tube from the intake floor avoids the necessity of any special formation of the outlet passage and the short length of the draft tube is particularly adapted for shallow outlets requiring only a limited depth of excavation.

This application is a division of my co-pending application Serial No. 674,461, filed November 13, 1923.

I claim:

1. In a hydraulic turbine, the combination with a runner of a draft tube having an outer wall flaring outwardly away from the axis and one or more relatively thin intermediate partitions subdividing the flow and formed with surfaces curved from a substantially axial direction at entrance to directions which diverge from the axis at discharge, the angle of divergence being greater in the partitions more remote from the axis and said partitions having successively greater discharge diameters.
2. In a hydraulic turbine, the combination with a runner of a draft tube having an outer wall diverging from the axis and one or more relatively thin intermediate partitions subdividing the flow and formed with surfaces curved from a substantially axial direction at entrance to directions which diverge from the axis at discharge, the angle of divergence being greater in the partitions more remote from the axis and the discharge portions of said partitions forming a series of co-axial straight-sided cones.
3. In a hydraulic turbine the combination with a runner of a draft tube comprising a central core and a plurality of annular passages concentrically disposed around said core, said core being continuous in contour with the runner hub, and said passages having approximately equal lengths when measured in the direction of the meridian components of the flow.
4. In a hydraulic turbine the combination with a runner of a draft tube comprising a central core, a plurality of concentric annular passages surrounding said core, and an outer wall flaring from substantially axial direction toward a radial direction, said core having a diameter at the discharge end less than one-third the diameter of the outer wall to provide a core which occupies a relatively small portion of the total discharge area.
5. In a hydraulic turbine the combination with a runner of a discharge passage, a draft tube comprising a central core extending to the floor of said discharge passage and supported thereby, and plate metal partitions of substantially uniform thickness forming a plurality of annular passages concentrically disposed around said core, having approximately equal lengths when measured in the direction of the meridian components of the flow.
6. In a hydraulic turbine the combination with a runner of a draft tube comprising a central core, and a plurality of annular passages concentrically disposed around said core, said core being continuous in contour with the runner hub and in close proximity thereto, and said passages having approximately equal lengths when measured in the direction of the meridian components of the flow.
7. A draft tube for a hydraulic turbine comprising a central core excluding the flow from the center of the tube and the surface of the core having a substantially axial direction at the discharge from the runner, an outer wall flaring from substantially axial direction toward a radial direction, and one or more intermediate partitions of plate metal construction having substantially uniform thickness, and said partitions dividing the flow into a series of concentric annular passages.
8. A draft tube for a hydraulic turbine comprising a central core and a plurality of concentric annular passages surrounding said core, the walls of said passages being substantially axial at entrance, and the length of the innermost passages measured in a meridian plane and in the direction of flow being substantially equal to that of the outermost passage.
9. In a hydraulic turbine having a runner the combination with a floor structure, of inclined stay vanes supported thereby and carrying a bearing structure for the runner shaft, a draft tube receiving the flow from said runner and comprising a plurality of concentric plate metal tubes spreading outward and dividing the flow into a plurality of spreading annular streams, the inner tubes being supported from the outermost tube which in turn is supported from said floor structure.
10. In a hydraulic turbine having a runner the combination with a sub-foundation structure forming the top of a discharge passage, of a draft tube projecting downward into said passage and comprising a series of concentric tubes of plate material and of generally conical form diverging outward from a central axis, the angle between successive cones with respect to each other being relatively small so that the angle of divergence of the tubes progressively decreases from a relatively large angle for the outer tube to a relatively small angle for the innermost tube.
11. In a hydraulic turbine installation the combination with a floor structure, of means thereabove forming an entrance passage or flume, a passage through said floor structure, an unshrouded propeller type runner in said passage, inclined fixed guide vanes supported from said floor structure above said runner and forming admission means to said turbine passage, said entrance passage or flume extending above and around said admission means, and a plural passage draft tube for said runner forming continuation of the passage in said floor.
12. In a hydraulic turbine installation the combination with a floor structure, of means thereabove forming an entrance passage or flume, a passage through said floor structure, an unshrouded propeller type runner in said passage, inclined fixed guide vanes supported from said floor structure and supporting a

- bearing for the shaft of said runner and providing admission means to said turbine passage, said entrance passage or flume extending above and around said admission means to permit flow of fluid thereto simultaneously from radial and axial directions, and a plural passage draft tube extending from the opening in said floor.
13. In a hydraulic turbine installation the combination with a floor structure, of means thereabove forming an entrance passage or flume, a passage through said floor structure, an unshrouded propeller type runner in said passage, fixed guide vanes supported from said floor structure above said runner and, forming admission means to said turbine passage, said entrance passage or flume extending above and around said admission means to permit flow of fluid thereto simultaneously from radial and axial directions, and a plural passage draft tube leading from said turbine passage and suspended from said floor structure.
14. In a hydraulic turbine installation the combination with a floor structure, of means thereabove forming an entrance passage or flume, a passage through said floor structure, an unshrouded propeller type runner in said passage, fixed guide vanes supported from said floor structure above said runner and forming admission means to said turbine passage, said entrance passage or flume extending above and around said admission means to permit of fluid thereto simultaneously from radial and axial directions, and a plural passage sheet metal draft tube leading from said turbine passage and suspended from said floor structure.
15. In a hydraulic turbine installation the combination with a runner, of a draft tube comprising a central core having a contour substantially continuous with that of the runner hub and in relatively close proximity thereto, and means forming a plurality of annular passages disposed around said core, the diameter of the discharge portion of said latter means being greater than that of said core adjacent the discharge.
16. In a hydraulic turbine installation the combination with a runner having a hub, of a draft tube comprising a central core having a contour substantially continuous with that of the runner hub and in close proximity thereto, and means forming a plurality of diverging annular passages disposed around said core, the diameter of said core at the point of discharge being less than the discharge diameter of the means forming said passages.
17. In a hydraulic turbine installation the combination with a runner having a hub, of a draft tube comprising a central core having a contour substantially continuous with that of the runner hub and in close proximity thereto, and means forming a plurality

of diverging annular passages substantially concentrically disposed around said core and said means including a relatively thin plate metal member having a greater discharge diameter than that of the discharge portion 70 of said core.

18. In a hydraulic turbine installation the combination with a runner having a hub, of a draft tube comprising a central core having a contour substantially continuous with 75 that of the runner hub and in close proximity thereto, and means forming a plurality of diverging passages surrounding said core, said means comprising relatively thin plate metal members so disposed that the general 80 outline of said draft tube is substantially fan shape.

19. In a hydraulic turbine installation the combination with an unshrouded propeller type runner, of a draft tube having means 85 forming a plurality of passages surrounding a common axis, said means comprising relatively thin partition members of substantially uniform thickness between their entrance and discharge edges whereby the discharges from 90 adjacent passages merge along a line which is substantially parallel to both sides of the partition forming said adjacent passages.

20. In a hydraulic installation the combination with a turbine runner, of a draft tube 95 comprising means forming a plurality of diverging passages disposed about a common axis, and a core for excluding water from the central portion of the tube, said means including a relatively thin plate metal member 100 forming the partition between the adjacent passages and said member having a discharge diameter greater than that of said core.

21. In a hydraulic turbine installation the combination with a turbine runner, of a draft 105 tube including means forming a plurality of substantially annular and concentric diverging passages, said means comprising relatively thin plate metal members forming inner 110 and outer walls and a similar member forming a partition therebetween, the diameters of said members at their discharge edges being different.

22. In a hydraulic turbine installation the combination with means forming an entrance passage floor having a vertical opening therethrough and a turbine runner associated with said vertical opening, of a draft tube having means forming a plurality of substantially annular and concentric diverging passages 120 and said means comprising relatively thin plate metal members having a depending relation to said floor and the outer one of said members being more horizontal than vertical.

23. In a hydraulic turbine installation the combination with means forming an inlet passage having a floor with a vertical opening therethrough and a turbine runner associated with said opening, of means forming a draft tube comprising inner and outer sub- 130

stantially annular and concentric members, and a partition between said members, said outer member flaring outwardly and depending from the lower surface of said floor so as to be spaced therefrom and having a discharge diameter greater than that of said partition.

24. In a hydraulic turbine installation the combination with a runner, of means forming a draft tube comprising a plurality of substantially annular and concentric diverging passages, said means including a partition comprising a plurality of substantially coaxial plate metal tubular sections having their adjacent edge portions held in operative relation to each other whereby said tubular members form a continuation of each other.

25. In a hydraulic turbine installation the combination with a runner, of means forming a draft tube comprising a plurality of substantially annular and concentric diverging passages, said means including a partition comprising a plurality of substantially coaxial plate metal tubular members having their adjacent edge portions held in operative relation to each other whereby said tubular members form a continuation of each other and certain of said tubular members are of substantially greater length than the length of others thereof.

26. In a hydraulic turbine installation the combination with a runner, of means forming a draft tube comprising a plurality of substantially annular and concentric diverging passages, said means including a partition comprising a plurality of sections formed as substantially coaxial tubular members having their adjacent edge portions held in operative relation to each other whereby said tubular members form a continuation of each other and said sections having a greater degree of flare as the discharge end of the draft tube is approached.

27. In a hydraulic turbine installation the combination with a turbine runner, of a draft tube comprising means forming a plurality of diverging passages, said means comprising relatively thin plate metal members so disposed that the general outline of said draft tube is substantially fan shape.

28. In a hydraulic turbine installation the combination with a turbine runner, of a draft tube having means forming a plurality of substantially annular and concentric diverging passages, said means comprising relatively thin plate metal members the outer one of which is more horizontal than vertical.

29. A multiple diffusing nozzle for converting the velocity of a fluid into pressure and constituted of a compound element having a plurality of passages each defined by uniformly diverging walls, the opposing walls of each passage enclosing angles of substantially 10° , the whole to the effect that the multiple passage nozzle possesses a total

outlet aperture considerably larger than that which could be obtained with a single passage nozzle having the same length and the same size of inlet orifice.

30. A high specific speed propeller type hydraulic turbine comprising, a draft tube, having a main divided passage providing a plurality of divisional diverging passages, the opposing walls of at least certain of said divisional passages enclosing angles of substantially 10 degrees throughout the major extent thereof, the whole to the effect that said divisional passages together have a greater outlet area than that which could be obtained with a single passage having the same length and size of inlet for said draft tube and a propeller type runner disposed in said passage and spaced from the entrance of said draft tube to provide a transition space therebetween.
